HANDLE

Gustaf Einar Lofgren, Riverside, Conn., assignor to Electrolux Corporation, Dover, Del., a corporation of Delaware

Application May 5, 1938, Serial No. 206,186

5 Claims. (Cl. 16—115)

My invention relates to handles and more particularly to a handle for carrying a vacuum cleaner or other article.

An object of my invention is to provide an improved handle of flexible material which fits snugly to the body or casing in a retracted position when not in use and which will withstand considerable strain.

Another object of my invention is to provide a handle secured with a fixed pivot at one end and a sliding pivot at the other end with means to prevent vibration of the pivot pins.

What I consider to be novel and my invention may be better understood by reference to the following specification and appended claims when considered in connection with the accompanying drawing, in which

Fig. 1 is a side view of a vacuum cleaner with my improved handle incorporated in it;

Fig. 2 is a plan view of the handle;

Fig. 3 is a sectional view of the handle and support taken along line 3—3 of Fig. 2;

Fig. 4 is a sectional view taken along line 4—4 of Fig. 3; and

Fig. 5 is a sectional view taken along the line 5—5 of Fig. 3.

Referring to the drawing, 10 indicates a vacuum cleaner unit of the type moved around the floor by a flexible hose 11 to which may be connected a cleaning tool 12 through the intermediary of a substantially rigid tubular member 13. When the cleaning unit 10 is not in use it may be desirable to carry it from one place to another for which purpose handle 14 is provided. Handle 14 is formed of a flexible material 15 such as soft molded rubber. In order to prevent the possibility of the flexible material 15 becoming permanently deformed in use and to increase its tensile strength, a stiffening member 16 is provided formed of a continuous strip 17 of fabric wound as a continuous belt in a plurality of layers.

Handle 14 is mounted on cleaner unit 10 by means of a fixed pivot pin 18 and a sliding pivot pin 19. As best indicated in Fig. 4, fixed pivot pin 18 is carried by upstanding ears 20 of the cleaner unit 10. A cover plate 21 encloses the ears 20 and the ends of pivot pin 18. Pivot pin 19 slides in slots 22 provided in a bracket 23 secured to casing 10. The ends of pivot pin 19 are enclosed in a cover plate 24. Handle 14 when not in use fits snugly to the body of cleaner unit 10 in a substantially horizontal position with the pivot pin 19 held in its most forward position in slots 22, shown at the left in Figs. 2 and 3. When

it is desired to lift the cleaner unit 10, the handle 14 is grasped and as it is raised the pivot pin 19 slides to the right as shown in Figs. 2 and 3 until it reaches the end of slots 22. Upon the application of further force the cleaner unit 10 may be lifted.

When the handle 14 is released after the cleaner unit 10 has been placed on a supporting surface, the handle 14 returns to its retracted position. The tensile strength of the flexible material 15 is supplemented by stiffening member 16 to enable the handle 14 to withstand considerable strain. As best indicated in Fig. 3, the stiffening member 16 is formed with a loop 25 surrounding pivot pin 18 and a loop 26 surrounding pivot pin 19. In the formation of the stiffening member 16, the strip 17 of fabric is wound in successive layers around mandrels to form the loops 25 and 26. The adjacent layers of the fabric strip 17 are secured together by means of an adhesive. After the stiffening member 16 has been formed the flexible material 15 is molded around it. The stiffening member 16 is arched downwardly at its two ends toward the loops 25 and 26 and is substantially straight throughout the remainder of its length. The stiffening member 16 is internally strained within the rubber covering 15 so that it will support the center part of the handle 14.

The flexible material 15 is provided with depending ends 27 and 28 which surround the loops 25 and 26 respectively of the stiffening member 16. Extending downwardly from the end 27 is a projection or lug 29. Lug 29 is formed integrally with the material 15 of handle 14 and is positioned at right angles to pivot pin 18 and substantially in front of the center line of the pivot pin. When the handle 14 is in its normal retracted position the lug 29 is in engagement with the casing of cleaner unit 10. Lug 29 tends to rotate handle 14 in a clockwise direction, as shown in Fig. 3, and assists in preventing the handle 14 from sagging in the middle. Lug 29 also produces a force upwardly due to the compression of the rubber which prevents the pivot pin 18 from rattling or vibrating in the ears 20 in the event of a relatively loose fit. A projection or flexible finger 30 extends downwardly from end 28 and parallel to the axis of pin 19. When handle 14 is in the retracted position, shown in Fig. 3, finger 30 curves to the right in contact with the casing of unit 10. When the handle 14 is arched upwardly upon use in lifting the cleaner unit 10 the free end of finger 30 tends to remain in position in contact

with the casing due to friction while the remainder of the finger 30 bends in a reverse curvature. Upon continued movement of the handle the finger 30 ultimately slides along the casing.

5 When handle 14 is in the retracted position, finger 30 produces a force upwardly which holds the pin 19 in the slots 22 against vibration or rattling.

After the flexible material 15 has been molded 10 around the stiffening member 16 the pins 18 and 19 are inserted through the depending ends 21 and 28 into the loops 25 and 26. The loops 25 and 26 tightly embrace the pins 18 and 19. The handle 14 is then secured to the casing of the 15 vacuum cleaner unit 10 by inserting the ends of pivot pin 18 in ears 20 and the ends of pivot pin 19 in slots 22.

What I claim is:

1. A handle for a vacuum cleaner including end 20 pins, sheet fabric tightly secured around said end pins and forming a connection between said pins, said fabric consisting of an endless belt with all parts between said pins secured tightly together, said belt having a straight center section and being 25 inclined downwardly at the ends to form an arch, and a soft rubber covering molded around said fabric having depending ends through which the pins pass, said fabric constituting the sole 30 stiffening means of the handle, said fabric being internally strained within the rubber covering for supporting the center part of the handle.

2. A handle for a vacuum cleaner casing including end pins, sheet fabric secured around said end pins and forming a connection between said 35 pins, a soft rubber covering molded around said fabric having depending ends through which the pins pass, a lug extending downwardly from

one of said depending ends and positioned at right angles to one of said pins, and a flexible finger extending downwardly from the other of said depending ends and positioned parallel to the axis of one of said pins, said lug and said finger engaging said casing to prevent vibration of said pins.

3. A handle for a vacuum cleaner casing including end pins carried by said handle, ears secured to said casing for engaging one of said 10 pins, a bracket secured to said casing and having slots to receive the other of said pins, a lug extending downwardly from one end of said handle engaging said casing adjacent said ears, and a flexible finger extending downwardly from the 15 other end of said handle and engaging said casing, whereby vibration of said pins is prevented.

4. A handle for a vacuum cleaner casing having longitudinal slots and upstanding ears, including end pins carried by said handle and engaging 20 said slots and said ears, a depending lug from said handle engaging said casing adjacent said ears adapted to prevent sagging of the handle in the middle, and a flexible finger extending downwardly from said handle and engaging said 25 casing adjacent said slots adapted to prevent vibration of the end pin in the slots.

5. A handle for a vacuum cleaner casing having upstanding ears and a bracket having longitudinal slots including a handle for said casing, 30 end pins carried by said handle and engaging said ears and said bracket slots, and depending projections from said handle engaging said casing and producing upwardly directed forces for holding said pins in the upstanding ears and bracket slots 35 against vibration.

GUSTAF EINAR LOFGREN.
